DESIGN FOR A PENHOLDER DESK STAND

Abraham Baff, North Arlington, N. J.

Application March 30, 1937, Serial No. 68,472

Term of patent 3½ years

To all whom it may concern:

Be it known that I, Abraham Baff, a citizen of the United States, residing at North Arlington, in the county of Bergen and State of New Jersey, have invented a new, original, and ornamental Design for a Penholder Desk Stand, of which the following is a specification, reference being had to the accompanying drawing, forming part thereof.

The characteristic feature of my design resides in the shape of the pen funnel and its base.

In the drawing:

Fig. 1 is a top plan view of a pen holder desk stand showing my new design.

Fig. 2 is a side elevation thereof.

Fig. 3 is an end view thereof.

I claim:

The ornamental design for a penholder desk stand, as shown and described.

ABRAHAM BAFF.
